UNITED STATES PATENT OFFICE

MEYER RICH, OF NEW LONDON, CONNECTICUT

DESIGN FOR A BOTTLE

Application filed April 28, 1931. Serial No. 39,647. Term of patent 14 years.

To all whom it may concern:

Be it known that I, MEYER RICH, a citizen of the United States, residing at 23 Hamilton St., city of New London, in the county of New London and State of Connecticut, have invented a new, original, and ornamental Design for Bottles, of which the following is a specification, reference being had to the accompanying drawing, forming part thereof.

The figure is a side view in elevation of a bottle, showing my new design. The appearance of the bottle is the same when viewed from the opposite side.

I claim:

The ornamental design for a bottle, as shown and described.

MEYER RICH.
